E. OTT.
EXPLOSIVE AND PROCESS OF MAKING SAME,
APPLICATION FILED MAY 25, 1920.
1,390,378. Patented Sept. 13, 1921.

UNITED STATES PATENT OFFICE.

ERWIN OTT, OF BASEL, SWITZERLAND, ASSIGNOR TO PROF. DR. EDWIN HANTON FAUST, OF BASEL, SWITZERLAND.

EXPLOSIVE AND PROCESS OF MAKING SAME.

1,390,378.

Specification of Letters Patent. Patented Sept. 13, 1921.

Application filed May 25, 1920. Serial No. 384,208.

To all whom it may concern:

Be it known that I, ERWIN OTT, a citizen of the German Republic, and resident of Basel, Switzerland, have invented a new and useful Explosive and a Process of Making Same, of which the following is a full, clear, and exact specification.

I have found that by acting with aqueous solutions of sodium azid on cyanure halogenids, there is obtained a new organic compound, the cyanure triazid, corresponding to the formula

which owing to its strongly explosive properties is capable of being used as an explosive.

The cyanure triazid constitutes in a pure state colorless crystals melting at 94° C., is not volatile, is not changed by cold water, 25 but is saponified slowly by hot water and explodes when it is subjected to violent concussion or heated to 170° C., or heated suddenly.

The cyanure triazid is an explosive substance particularly able of being employed as a priming agent. It is not poisonous, resistant to moistness and to light, does not attack metals, is superior as priming agent to pure fulminating mercury, prepared 35 fulminating mercury, lead azid and silver azid, is better adapted for the preparation of Flobert ammunition and ammunition for other small fire arms than fulminating mercury and lead azid and forms 40 in the molten state an excellent solvent for the most organic substances usually employed as explosives for grenade loadings, torpedoes etc. and can therefore be added to the same.

45 The preparation of the triazid is preferably carried out by acting with an excess of sodium azid in an aqueous solution, in the cold, on cyanure chlorid gradually suspended in the said solution.

50 The invention is illustrated by the following examples:

Example 1.—6.2 gr. of finely pulverized

cyanure chlorid are introduced, gradually, in very small portions, in the course of 1 to 2 hours, into a solution of 7 gr. of sodium azid in 70 ccm. water, while cooling and continuously stirring strongly. Under these conditions no inconvenient and detrimental lumping of the mass takes place. The heavy, crystalline powder of the chlorid is gradually transformed into the light flaky triazid. When all cyanure chlorid has been introduced, the precipitate is left still for 2-7 hours, in the cold, in contact with the solution, then separated by suction, washed with water and dried in the air. The yield of the raw product showing a constant weight, is of 5.68 gr. or 83.5 per cent. of the theory. The raw product can be employed directly, it contains about 80 per cent. of pure triazid.

If in this example instead of 7 gr. of sodium azid there are employed 9-10 gr. of the same body for the same quantity of 75 6.2 gr. of cyanure chlorid, the yield arises to 6.2 gr. or 91 per cent. of the theory and the raw product obtained is accordingly of a higher value.

If the raw product prepared, as described, from 6.2 gr. of cyanure chlorid and 7 gr. of sodium azid is, after it has been washed and before it has been dried, introduced into a fresh solution of 2-3 gr. of sodium azid in 20 ccm. water and left in contact with the said solution for several hours in the cold, there results a yield of 6.3 gr. of raw product or 92.6 per cent. of the theory.

All these raw products give chemically pure triazid C_3N_{12} , by a single crystallization from a small quantity of boiling alcohol, in which the cyanure triazid is readily soluble, when hot, but difficultly soluble when cold.

From the mother-liquors resulting from the preparations the sodium azid employed in excess can be recovered in a pure state and without loss by acidifying the said liquors with the necessary quantity of dilute acids, distilling off the aqueous azoimid, collecting hereby only a small quantity of the first fraction of the distillate and evaporating it, after neutralization with soda lye (caustic soda).

It is consequently possible to transform,

according to this process, cyanure chlorid with sodium azid, without any loss of sodium azid, into cyanure triazid C_3N_{12} with yields of over 90 per cent. of the theory.

- 5 The chemically pure cyanure triazid C_3N_{12} constitutes colorless crystals melting at $94^{\circ} C.$ and is not volatile. It is not affected by cold water and only slowly saponified by hot water. It is relatively insensitive 10 to friction and not too strong concussion, but explodes by impact, or when heated to $170^{\circ} C.$ or when heated suddenly. It is not more sensitive to frictions and shocks than fulminating mercury.
- 15 By its explosion, it acts on other explosives, particularly such which explode difficultly, its priming action surpassing those of all hitherto known priming agents. In 20 sides the complete absence of heavy or precious metals, a great number of essential advantages, namely:

- (1) It is not poisonous in contradistinction to fulminating mercury and lead azid.
- 25 (2) It is not sensitive, that is to say not affected by moisture in contradistinction to fulminating mercury.
- (3) It is resistant to and not changed by light in contradistinction to lead azid and to 30 silver azid.

- (4) There is no danger of reaction with a metal of the material of the detonator casting or capsule-shell, as is the case with lead azid which forms dangerous metal 35 pounds, as for instance CuN_6 , according to the formula $PbN_6 + Cu = CuN_6 + Pb$.

- (5) In contradistinction to the hitherto employed priming agents it is fusible and its fusion point ($94^{\circ} C.$) is so low that the 40 product melted by a single heating on water or steam bath, can be poured without danger in the capsule shell. It solidifies therein after cooling and shows the density (specific weight) of 1.5.

- 45 (6) The superiority of the cyanure triazid over the fulminating mercury as well in a pure as in a commercial state, and over the lead and silver azids is explained by the following example:

- 50 *Example a*.—1 gr. of trinitrotoluene is melted in a copper capsule shell No. 8 and forms therein after solidifying a column of an average height of 20.5 mm. If 0.3 gr. of cyanure triazid are set thereon and the 55 bursting capsule fired on a lead plate, the trinitrotoluene will explode entirely. None of the other priming agents can produce such a complete explosion of an analogous column of trinitrotoluene, even when set 60 thereon in quantities up to 1 gr. Only with prepared commercial fulminating mercury applied in a quantity of at least 1 gr., the above entire column of trinitrotoluene begins to explode completely.
- 65 In all other cases, particularly when em-

ploying smaller quantities of the priming agent, residues or remainders of the trinitrotoluene column could be measured with a slide-gage and from the difference between these remainders and the original height of 70 20.5 mm. of the column the height of the exploded trinitrotoluene column may be calculated.

The entry of these heights on the ordinates of a system of coördinates, while the 75 quantities of priming agents are marked on the abscisses, permits of showing graphically the priming actions of the priming agents employed, as shown in the accompanying diagram.

80 *Example b*.—A cartridge, lying free and not inclosed, containing an explosive load of 94 gr. of ammonium nitrate sieved through a sieve having 3600 meshes per square centimeter and of 6 gr. of colophony is exploded completely by 1 gr. of cyanure triazid poured in a melted condition into a copper capsule-shell No. 8 and left solidify therein, in analogous manner as by 1 gr. of prepared fulminating mercury.

90 If on 0.5 gr. of trinitrotoluene poured in a melted condition into a copper capsule-shell No. 8 and left solidify therein, there are set only 0.5 gr. of triazid, this detonating composition will produce in the same manner the entire explosion of the above specified cartridge containing 100 gr. of explosive substances.

95 (7) In contradistinction to the other priming agents cyanure triazid is an excellent solvent for most organic substances particularly for all aliphatic and aromatic nitro-compounds, which are usually added for various purposes, for instance to grenade charges, torpedoes etc., for increasing the 100 sensitiveness or for increasing the explosive effect.

105 Trinitrotoluene and triazid can be mixed in any proportion in a molten state and do not separate again by cooling. Also many salts of organic acids are considerably soluble in molten triazid; for instance lead picrate dissolves in molten triazid up to 20 per cent. and does not separate again on solidification.

110 (8) It has been determined that the cyanure triazid in spite of its very much higher priming actions, is much less brisant than fulminating mercury and lead nitrid and is therefore more appropriate for the 115 manufacture of Flobert ammunition and of ammunition for other small fire-arms than both these latter substances.

What I claim is:

1. The herein described process for the 125 manufacture of cyanure triazid, consisting in treating aqueous solutions of sodium azid with a cyanure halogenid.

2. As a new explosive particularly capable of being employed as a priming agent,

the herein described cyanure triazid corresponding to the formula

5

constituting in a pure state colorless crystals
10 melting at 94° C., and being not volatile,
being not changed by cold water, but being
saponified slowly by hot water and exploding
when subjected to violent concussion, or
heated to 170° C. or heated suddenly, the
15 said cyanure triazid being further not poisonous,
resistant to moisture and to light,
not attacking metals, being superior, as
priming agent, to pure fulminating mer-

cury, prepared fulminating mercury, lead
azid and silver azid, being more appropriate 20
for the preparation of Flobert ammunition
and of ammunition for other small fire-arms
than fulminating mercury and lead azid
and being in the molten state an excellent
solvent for the most organic substances usu- 25
ally employed for grenade loadings, tor-
pedoes etc., and being therefore capable of
being added to the same.

In witness whereof I have hereunto signed
my name this 7th day of May 1920, in the 30
presence of two subscribing witnesses.

ERWIN OTT.

Witnesses:

JOHN H. LORD,
AMAND RITTER.
